UNITED STATES PATENT OFFICE.

HERBERT J. ADAMS, OF BATTLE CREEK, MICHIGAN.

FILING-CASE FOR MAPS.

1,335,415.

Specification of Letters Patent. Patented Mar. 30, 1920.

Application filed September 21, 1918. Serial No. 255,137.

To all whom it may concern:

Be it known that I, HERBERT J. ADAMS, a citizen of the United States, residing at Battle Creek, in the county of Calhoun and 5 State of Michigan, have invented a new and useful Filing-Case for Maps, of which the following is a specification.

The purpose of my invention is to provide a compact receptacle for maps, drawings, charts, tabulations, pictures and similar articles, insuring means for greater safety than now known against the wear and tear of such articles when frequently referred to, and affording a greater degree 15 of convenience in the filing, selection from the mass and withdrawal therefrom, of such articles, and for inspection of them while attached to the case, the provision being for hanging the maps flat therein and withdrawing the same practically without interference by others.

I attain these objects by the mechanism illustrated in the accompanying drawings, in which—

25 Figure 1 is a front view of the interior of the case with the door opened down to horizontal plane, carrying the cover and supported on the ribs, also a map hung by right and left hanger clips and one map 30 supported at the center by a single clip, maps being identified in the drawings by numeral 28.

Fig. 2 is an end view showing the door open to a point short of separating the spindle and socket. Fig. 3 is a similar view showing the spindle and socket separated for filing maps, and in dash line showing the door supported on the ribs.

Fig. 4 shows top portion of door and portion of cover riding same and the door-checking mechanism. (See plan view Fig. 9.)

Fig. 5 shows the parts of the hanger-clip out of position. Fig. 6 is the clip fastened 45 to a map, and the marking plate, both strung on the spindle shown as to a portion. Fig. 7 shows portion of the rib with the door hinge-arm thereon in position for supporting the door in horizontal position.

50 Fig. 8 is a view in perspective of the separating plate. (An end portion of the same is shown in Fig. 1.) Fig. 9 is a plan view of the door-checking mechanism. Fig. 10 is a view in perspective of the button in position holding the door and cover closed.

Fig. 11 shows the beards near the points of the spindle and socket.

Similar numerals refer to similar parts throughout the several views.

The inclosing parts of the case consist of 60 the back wall 1 the end walls 2, 2, the floor 3, the door 4, forming when closed the front wall, and the cover 5, all preferably made of material suited to other office furniture, the back and end walls and floor being permanently fastened together. In closed position the door fits in between the end walls, floor and cover, and swings open and shut on the curved lower ends of the ribs 25, hereinafter described, and clear of the floor. 70 The cover, carrying door-checking hook-arms hereinafter described, is inserted to closing position between cleats on the end walls on the front edges of which the buttons 16—16, carrying lugs 17 17, are pivoted. 75 When in position holding the door and cover closed (Fig. 10) the lug bears flat against the end wall. When turned out of such locking position the lug swings down to bear edgewise against the wall, the pivot 80 hole in the button being eccentrically located, making it "top-heavy," so that it will have tendency to rest either fully in, or fully out of, latching position. The flanges, or angles, shown on the button are only wide 85 enough for stiffening merely, in case the material, preferably sheet metal, is so thin as to require it, the buttons being necessary only when it is required to move the case about. The front edge of the cover is made 90 extra thick with a shoulder forming a pull. Similar cleats are carried by the back wall to stay the back edge of the cover.

The filing mechanism consists of spindle 7, fastened to the back wall and forwardly 95 projecting and the corresponding rearwardly projecting socket 8, fastened to the door, both being in length approximating the horizontal depth of the case, and being formed longitudinally to describe arcs of a 100 circle centering at the bottom of the door, and are in relative position causing the socket to entirely ensheathe the spindle upon closing the door. The spindle and socket are made of metal and are each stiff enough 105 to support all the maps filed in a case having one spindle and socket only, without sagging, when not united with the other. The socket is beveled off on top at its point permitting it when inclosing the spindle 110

to slide freely through the openings in the map-hangers, marking plates and separating plate (hereinafter described) that may be strung upon the spindle.

5 Only one spindle and corresponding socket is essential to my invention, that consideration being one of several distinguishing it from the well-known loose-leaf binders, two or more spindles and corresponding sockets being conveniently used for adjusting, as nearly as may be, the capacity of the case for map sheets to that required of one or more sockets for the corresponding hanger-clips and marking plates, 15 when the case is closed.

Hanger-clips are provided to grip the edges of maps and for stringing on the spindle or socket, one or more being used for each map according to convenience, composed of the folio 19, preferably made of sheet metal, having holes in one leaf (Fig. 5) and two slits in line of the fold, and an L-shaped bar, or square 20, carrying knobs 21 21. I prefer to form the square by folding a straight bar of sheet metal and pressing the fold down flat only after inserting the knobbed legs through the slits with the knobs registering in the holes, the legs being thus spread beyond the limits of the slits, so that the square is locked in the folio, but movable permitting the knobs to be carried beyond the edge thereof. Upon inserting the edge of a map in the folio above the knobs and drawing the knobs opposite the holes it is bound in the folio ready for stringing upon spindle or socket through the space then acquired inside the angle of the square. Maps having a dimension greater than the height of the case or 40 its width between the end walls may be conveniently filed by using the hanger-clips on opposite edges of the map, resulting in a horizontal fold when suspended, or by using two or more of the hanger-clips on the same 45 edge, and inserting the map in the case folded, such a fold then standing in vertical position at the left or right, as the case may be, of the spindle and socket support, or supports. In either case both leaves of the 50 folio are independently supported. In case the mass of maps filed embrace a variety of sizes usually the above manner of filing the over-sized maps referred to would involve little danger of creasing them at such 55 folds.

A plate 22, preferably made of thin sheet metal is provided for carrying a marking card for each map filed, (Fig. 6) the same having a hole large enough to receive the socket freely, and at one side of the weight center, and having folded edges, the hang of the plate on the spindle or socket tending to hold said edges vertical, which carry inserted between them a marking card above the hole, the folded edges at the same time

stiffening the plate which serves also as a buffer in the use of the separating plate mentioned.

Said separating plate 18, is made of sheet metal, in length horizontally spanning the maps filed, has a slot in the blade correspond to each socket used for letting it down in vertical plane between the maps, and has a fold in the upper edge for a hand hold and stiffening, and serves to shove all 70 maps on either side, simultaneously when more than one spindle is used, onto the spindles and sockets respectively when the door is to be opened for filing or withdrawing maps, and is then left to rest against 75 those remaining on the spindles, or spindle, as the case may be, holding their tops from buckling. (Fig. 8, and Fig. 1 partly cut away.)

The door is hinged, or anchored, to the 80 case (see Figs. 3 and 7) by arms 23 23, carried on the bottom corners thereof and projecting into the case. The flat shelf bracket known to commerce, when slotted in an edge at the angle serves for these arms, 85 the slot in each arm affording travel-way for the vertical ribs 25 25, on said end walls, the wings 24 24, formed by the slots in the arms lapping behind the ribs, which carry 90 series of teeth 26 26, at corresponding 95 heights. The maps are preferably filed facing the back, so that when the door is opened wide the top map of the mass strung on the sockets is exposed to view. Raising the door to desired height on the ribs and 100 settling it to horizontal plane the legs of the arms fastened to it engage said teeth at the lower edges of the slots, the arms being fastened to the door in position to hold it clear of the teeth, the opposing bearing 105 thus induced against the ribs, in conjunction with the leveling teeth, sustains the door in such horizontal open position. The lower ends of the ribs are curved forward 110 27 27, serving as bearings for the door in 115 swinging open and shut.

I provide mechanism for checking the door in differing open positions, as follows: (detail views 4 and 9.) The hook-arms 9 9, are fastened to the cover near its 115 back corners, and project into the case, being preferably made of spring steel. They have hook formations 10, 10, directed cross-wise the cover and slanting toward it causing them upon drawing the cover forward 120 from its horizontal position on the case and tipping it flat against the top of the door to lodge on the edge of the latter. In such position hooks 11 11, are in line to engage 125 on swinging the door outward, the lugs 12 12, on the horizontal bars 13, 13, sliding each through a single staple on the end walls and guided and held back along same by weights 6 6, attached to cords 14 14, connecting weights and bars and passing 130

through loops fastened to the back wall, engagement of said hooks and lugs taking place when the door is opened to position short of disconnection of spindle and socket 5 to effect spreading of the hanging space thereon for convenient "cutting out" of a particular map filed or to make way for filing. At the convenience of the operator either the right or left end of the cover may 10 then be shoved down causing the corresponding hook 10, to impinge on the door throwing the corresponding hook and lug out of engagement and relieving the pull on the door from one of the weights. This allows 15 the door to be more easily swung farther outward to position of separation of spindle and socket sufficient for convenient insertion or withdrawal of maps, the movement drawing out its full length the remaining 20 horizontal bar, release of the door from which then being afforded by depressing to impinge on the door the end of the cover remaining up in first position mentioned, and the door may then be adjusted to horizontal 25 position by grasping the same by its edges in any manner convenient to the operator. For clearness of illustration I have described and shown the weights mentioned, but where it is necessary for much moving 30 of the case about I would prefer substituting for the weights tension springs requiring very little space and anchored to the case below the bars.

As shown in Fig. 11 beards 29 and 30, 35 are formed on the spindle and socket respectively to prevent the parts strung thereon from being jarred or shoved off when the stringing space is filled to capacity or nearly so or when there has been inadvertent failure to properly assemble the maps before separation of said spindle and socket. The beards are formed at positions on the spindle and socket below their upper planes, and do not interfere with stringing 40 or removing sheets on or from the spindle and socket since their removal involves slightly lifting them from the top; and when the spindle and socket are telescoped the beards are out of range of the bearing 45 edge of the sheets or sheet hangers, and so are rendered inoperative as keepers, or retainers, against accidental slipping off of the sheets, and become neutral and ineffectual to interfere with the free shifting of the sheets or hangers from either one, the 50 spindle or the socket, to the other.

Unless it is desired to fasten the case to the room wall it is convenient to use braces, for which purpose the kind of bracket supports mentioned will do, fastening them inverted to the front edges of the end walls of the case with one leg projecting along the floor of the room. The cover having horizontal position on the case is partially in 55 view of economy in vertical space, the better

permitting one case to rest on top of another, such brackets as mentioned serving when fastened in normal position to the upper ends of said end walls of one case to support a case above it similarly equipped 70 with braces at the bottom.

In operation of the filing case, starting with the cover closed, it is released by turning the buttons, drawn forward and tipped down flat against the outside of the door 75 which is then swung outward until checked by engagement of the hooks projecting from the cover with the lugs projecting inward from the bars on the end walls, the movement resulting in withdrawing the spindle 80 to position nearly clear of the socket for shifting a portion or all of the mass of maps suspended on the latter onto the former, and for "cutting out" a particular map to be withdrawn, or a particular location in 85 such mass for the insertion of one, upon separation of spindle and socket. Upon depressing one end of the cover down on the door to the point of relieving the corresponding hook-lug engagement the door is 90 then opened to the limit of forward movement of the lug opposite the other end of the cover, which movement of the door leaves the sockets and spindles separated for the insertion or withdrawal of a map. Depressing 95 said other end of the cover on the door relieves it from the remaining hook-lug engagement when the door may be opened as much wider as desired or adjusted on the case in horizontal plane as hereinbefore described. I make the teeth on the ribs by slashing the edges thereof and setting forward the under lips, and tipping the front edge of the door up withdraws the anchor arms from seat on the teeth, allowing ribs 100 and teeth to pass through the slots in the arms as the bottom of the door is lowered 105 to position for closing tight without mechanical interference, the tension affecting the bars on the end walls having drawn 110 them back into the case.

Having fully described my invention, what I claim as new and desire to secure by Letters Patent is:—

1. In a structure of the class described, 115 the combination with a casing comprising rear and end walls, a door for the front of said casing, uprights on the end walls, brackets at the lower end of said door engaged with said uprights for vertical and swing- 120 ing adjustment thereon so that the door may be tilted or adjusted to a horizontal position at different elevations, a sliding cover for said casing collapsible against the front of the door and provided with arms having offsets therein engageable with the upper edge of the door for supporting the cover in its collapsed position, and counterweight slides mounted on said end walls to be engaged by said arms when the door is opened 130

for counterbalancing and supporting it in partially open position.

2. In a structure of the class described, the combination of a casing, a door and means for mounting the door at its lower end for pivotal and vertical adjustment so that it may be tilted or elevated and adjusted to a horizontal position, a cover adapted to collapse against the front of the door and provided with an arm projecting rearwardly when so collapsed, and a counterbalance member adapted to be engaged by said arm to support the door in tilted position.

3. In a structure of the class described, the combination of a casing, a door and means for mounting the door at its lower end for vertical and pivotal adjustment so that it may be tilted or elevated and adjusted to a horizontal position, a cover adapted to collapse against the front of the door and provided with an arm projecting rear-

wardly when so collapsed, and a counterbalance member adapted to be engaged by said arm to support the door in tilted position, coacting telescoping spindle members on the door and casing adapted for supporting sheets or sheet hangers strung thereon and for permitting the sheets to be freely shifted singly or in mass from one spindle member to the other when they are telescoped, upwardly projecting beard members integral on the ends of the spindle members adapted for retaining the sheets from accidentally slipping off the spindle members when they are separated while permitting their free manual stringing thereon or removal therefrom, and for being automatically rendered neutral, and non-interfering with the shifting of said sheets on said spindle members when they are telescoped.

HERBERT J. ADAMS.
